UNITED STATES PATENT OFFICE.

AMOS FLOYD CURTRIGHT, OF MEEKER, COLORADO.

INSULATOR FOR ANTENNAE.

Application filed March 13, 1925. Serial No. 15,296.

This invention relates to electrical insulators and particularly to an insulator of the suspension type which is especially adapted to the support of antenna wires for 5 the transmission and reception of radiant energy.

The object of the invention is to produce an insulator which interposes an extended dielectric surface between the antenna wire 10 and the suspension means; which provides for the enclosure of the end of said wire within a sheath of insulation, thereby avoiding leakage losses from the angular edge of the end of the wire; which facilitates the 15 securing of the antenna wire; and which provides means for safeguarding the insulator from lateral strains that may arise from swaying of the antenna in the wind.

Other objects of the invention will be disclosed as the following description of the preferred embodiment thereof develops.

In the drawings:

Figure 1 is a longitudinal section through an insulator embodying my invention.

25 Figure 2 is a cross section taken along the line 2—2 of Figure 1.

Figure 3 is a cross section taken along the line of 3—3 of Figure 1.

30 Figure 4 is a cross sectional view of a modified form of disk.

Figure 5 is a longitudinal section through an insulator embodying my invention in a slightly modified form, means being provided for an integral lead-in.

35 Figure 6 is a similar view of the insulator to that shown in Figure 4, arranged for use without the lead-in.

Figure 7 is a cross section taken along the line 7—7 of Figure 6.

40 Referring now in detail to the several figures, the numeral 1 represents an insulating element having a perforation or eye, through which a rope or cord 3 is run, the same providing means for supporting the insulator.

45 Said insulating element is formed with an integral skirt or sheath 4, the latter being of general cylindrical form and adapted to surround the terminal portion of the antenna wire. The reference character 5

50 represents the antenna wire which extends within the skirt or sheath of the insulating element and is secured to the latter by being run through the eye 7 formed in a boss 8 which projects into the chamber within

55 said skirt.

It will be apparent that one of the chief

objects of the skirt is to provide a long leakage path between the antenna wire and the rope or other supporting means, and since the normal position of the insulator is that 60 in which its longitudinal axis lies along the catenary of the antenna wire, the open end of the skirt will be directed downwardly and a considerable portion of said leakage path will be positively protected from direct 65 exposure to rain or other atmospheric moisture. The outer end of the insulating element is preferably formed with an abrupt flare to assist in draining away moisture from the open end of the skirt. 70

It is essential to the efficiency of the insulator that the interior wall of the chamber within the skirt be kept free from a deposit of dust, which, due to its hygroscopic nature, reduces the dielectric density of the 75 leakage path. A closure for said chamber therefore becomes essential, which I have provided in the form of a disk 9 of mica, a phenolic condensation product, or other suitable insulating substance, perforated in 80 the center as indicated at 10 in Figure 1 and strung upon the antenna wire before the latter is attached to the insulating element. In that form of the invention illustrated in Figure 1 the interior of the skirt of the insulating element is slightly tapered in a direction away from its open end, in the manner shown at 11 and the disk 10 is of such size as to jam against said tapered wall at a point slightly inside the flared end of the 90 insulating element, thereby not only effectively sealing the chamber within the skirt against ingress of dust but also excluding frost and moisture. The taper of the skirt is of that gradual degree known as a "sticking" 95 taper, so that the disk is frictionally retained in place and will not become dislodged by swaying of the antenna. Although the radius of the disk 9 is less in length than the length of the leakage path afforded by the surface within the skirt of the insulating element, yet the substantially vertical disposition of the disk ensures the surface thereof against the collection of a deposit of dust or other foreign substance, 100 so that the dielectric value of the leakage path along said disk is not less than that of the leakage path of the said insulator, and the dielectric efficiency of the device is not diminished by the employment of the disk. 105

It is well known that considerable leakage of electrical energy takes place at points

or sharp edges of conductors. By having the wound portion 12 of the end of the antenna wire enclosed within a chamber having non-conductive walls, leakage from the 5 corrugated contour thereof is substantially eliminated.

It will be noted that the eyes 2 and 4 are relatively close, so that if the antenna wire is hung slack, an arcuate movement of the 10 eye 7 about the eye 2 may take place due to stretching or sagging of the antenna wire as it sways in the wind. Were it not for the disk 9 this would cause an arcuate movement of the open end of the insulating element 15 of considerable amplitude, bringing it into contact with the antenna wire, possibly with disastrous results to the skirt of the insulating element, but the disk 9 acts as a spacer, holding the antenna wire at all 20 times out of contact with the insulating element.

It is contemplated to make the insulating element of glass, porcelain or other suitable nonconductive substance, but when making 25 it of baked ceramic material, manufacturing difficulties may arise, due to warping of the skirt during the baking process, so that it may be found desirable to dispense with the "sticking" taper of the interior wall of 30 the skirt, as a means for holding the disk 9 in place and to make the skirt cylindrical inside as well as on the outside. The disk 9 may then be provided with a soft rubber thimble 12 at its center as shown in Figure 35 4 which frictionally engages the antenna wire. The disk, in this instance should have an easy fit within the skirt, so that it can be pushed into the skirt chamber as far as may be desired without hindrance from 40 any slight inequalities in the shape of the wall of the skirt.

Figures 5, 6 and 7 illustrate a modification of the invention which is equally adaptable for either end of the antenna where one 45 end of the latter is integral with the "lead-in" wire. In this form of the invention the insulating element remains the same as in the first described form, but the insulation disk is made of two disks, 13 and 14 frictionally rotatable about the soft rubber 50 thimble, and relatively to one another. The disks are provided with perforations 15 and 16 which register in one relative position of 55 said disks as shown in Figure 5, and are out of registry, in another relative position, as shown in Figures 6 and 7.

When the insulator is used at the remote end of the antenna, that is to say, the end 60 remote from the "lead-in" the disks are placed in a position with the perforations out of registry, constituting an imperforate closure for the skirt chamber. When it is desired to have a part of the antenna wire 65 pass out of the skirt chamber, as an integral "lead-in," the disks are arranged with the

apertures 15 and 16 in registry, forming a single passage 17, Figure 5, through which the "lead-in" wire 18 may pass the latter being extended to any desired point outside the insulator. It is to be understood that 70 when the antenna wire is being manipulated to secure it to the insulator the disk 9, in Figure 1, or the disks 13 and 14 in Figures 5 and 6, as the case may be, are pushed out along the antenna a sufficient distance to be 75 out of the way.

While I have now described a form of the invention which may be regarded as elemental in its simplicity it is to be understood that variations in the practical embodiment of the same may from time to time be made to suit the exigencies of use without transcending the scope of the invention.

Having described my invention what I claim as new and desire to secure by Letters 85 Patent, is:—

1. In combination with a conductor, an insulating element provided with a skirt forming a chamber surrounding a portion of said conductor, said insulating element 90 having an eye within said chamber for the attachment of said conductor and an external eye for the support of said insulating element, and an insulating piece slidable upon said conductor to a final position within the skirt of said insulating element, forming a closure for said skirt chamber.

2. An insulator comprising an insulating element adapted to form a dielectric link between a suspended conductor and a support, 100 said insulating element being provided with a skirt forming a chamber adapted to surround a portion of said conductor, and a disk of insulation material constructed to frictionally engage said conductor and to 105 be slidably moved thereupon, said disk forming a closure for said skirt chamber when moved to a position within the open end of said skirt.

3. An insulator comprising an insulating element having a portion thereof adapted to be normally tensioned between a suspended conductor and a support, said insulating element being provided with an untensioned skirt forming a chamber adapted to surround a portion of said conductor, and a closure for the open end of said chamber comprising an insulating member adapted to be slidably mounted upon said conductor and movable to a closing position within 115 said skirt chamber.

4. An insulator comprising an insulating element having a portion thereof adapted to be normally tensioned between a suspended conductor and a support, said insulating element being provided with an untensioned skirt forming a chamber adapted to surround a portion of said conductor, and a closure for the open end of said chamber comprising an insulating member adapted to 120 125 130

- frictionally engage said conductor and to be slidably movable thereupon to and from a closing position with respect to said skirt chamber.
5. An insulator comprising an insulating element having a portion thereof adapted to be normally tensioned between a suspended conductor and a support, said insulating element being provided with an untensioned skirt forming a chamber adapted to surround a portion of said conductor, and a closure for the open end of said chamber,
- 10

adapted to be slidably mounted upon said conductor and movable to a closing position with respect to said skirt chamber, said closure including a pair of contiguous disks each provided with an aperture eccentrically thereof, said disks being relatively rotatable, selectively to bring said apertures into or out of alignment.

In testimony whereof I have hereunto set my hand.

AMOS FLOYD CURTRIGHT.
